ABSTRACT OF THE DISCLOSURE

A component tube for a muffler is formed with the ends parallel to each other and slanted to the tube axis so that when mounted in supporting flanges the tube contains material that overlaps substantially less than all of the flange thereby effecting a substantial saving in the amount of metal used in the tube.

My invention relates to mufflers and in particular to mufflers manufactured in huge quantities such as automobile exhaust mufflers.

It is an object of my invention to reduce the cost of mufflers without in any way interfering with their quality and performance.

The invention accomplishes the foregoing by shaping the ends of the tubular parts used in mufflers so that they lie in a plane which is diagonal instead of normal to the axis of the tube. In this way a small saving in material is made for each tube which, when totaled up for the several tubes in a muffler and for the millions of mufflers manufactured, amounts to a very substantial saving in cost of metal used to fabricate the mufflers.

The invention is illustrated in the accompanying drawings, in which:

FIGURE 1 is a longitudinal cross section for a typical exhaust muffler;

FIGURE 2 is an enlarged cross section along the line 2—2 of FIGURE 1;

FIGURE 3 is an enlarged view of the structure within the circle 3 of FIGURE 1; and

FIGURE 4 is a reduced view showing the blank that may be used to form the tubes used in the muffler.

The muffler 1 has an outer shell 3 which may be surrounded by a layer of asbestos and metal to provide insulation 5. The inlet end of the housing 3 is closed by the header 7 and the outlet end by the header 9. Spot welded in position inside of the shell 3 are flanged partitions 11, 13 and 15 which define longitudinally separated chambers 17, 19, 21, and 23 within the muffler shell 3. Extending through the inlet header 7 and supported in a flange 25 formed therein is an inlet bushing 27. The inner end of the bushing 27 extends through and is spot welded to a flange 29 in the partition 11. Supported in the inner end of the bushing 27 is the inlet end of a gas flow tube 31 and this extends through a necked opening 33 in partition 13 and is supported in a flanged neck 35 in the partition 15. The partitions 13 and 15 also have a pair of flanged necks 37 and 39 which support the opposite ends of a return flow tube 41. The partitions 13 and 15 also have flanged necks 43 and 45 which support an outlet tube 47 which also extends into an outlet bushing 49 that is formed in the header 9.

The portions of tubes 31, 41 and 47 within the chamber 21 are louvered as indicated in the drawings, and the

2

louvers in tube 31 are surrounded by a double pancake construction 51 which provides a pair of small volume spit chambers 53 for silencing relatively high frequencies and roughness in the gas. The chamber 17 is connected through a tuning tube 55 to the chamber 19 and therefore acts as a Helmholtz resonator that may be tuned to silence a selected relatively low frequency in the gas passing through the muffler.

Exhaust gas enters the inlet bushing 27 and passes along the pipe 31 into chamber 23 where it reverses direction to flow forwardly through the return flow tube 41. In chamber 19 it reverses flow again and passes out of the muffler through the tube 47. While the gas is in the various tubes within the chamber 21, the connection with the volume of the chamber through louvers in the tubes or with the spit chamber 51, enables high and medium frequencies to be attenuated. As already indicated relatively low frequency is attenuated by means of the Helmholtz resonator comprising chamber 17 and tuning tube 55.

In accordance with the invention and as visible in the drawings certain of the tubes, namely, 31, 41, 47, and 55 have the opposite ends formed on a bias or taper, the opposite ends being parallel to each other. The angle of the end faces with respect to the axis of the tube is small enough so that tubes can still be adequately supported in the various partition flanges and welded to them where desired.

Assuming that the various tubes are formed by rolling up originally flat sheet metal as indicated by the tube interlock joints in FIGURE 2, it will be seen from FIGURE 4 that the effective length 57 of the tube and blank is somewhat greater than the actual blank lengths 59 because of the slanted ends 61 and 63. Accordingly, there is a saving in material which when multiplied by millions of units amounts to something which is quite substantial. The same saving can be effected in tubing that is of the seamless type by cutting off the individual pieces of tubing along the parallel diagonals as indicated.

It will now be realized that the invention provides an effective expedient for substantially reducing the total material cost of mufflers when manufactured in high production and that this is done without interfering with the performance or quality of the muffler.

Variations in the specific structure illustrated may be made without departing from the spirit and scope of the invention.

I claim:

1. A muffler for silencing gases comprising a housing having an inlet and an outlet, means inside said housing for conveying gases from the inlet to the outlet and silencing gases within the housing, said means including a tube having opposite ends, said tube having an axis, said opposite ends being parallel to each other and making an angle with said axis which is different than 90°, tube support means in said housing for each end of said tube and each tube support means having an opening and an annular flange around said opening, said annular flanges being coaxial with said tube and the planes of each opening being perpendicular to the axis of the tube, the ends of said tube being mounted in said annular flanges, the length of said flanges and the angle of the ends of the tube being such that the axial length of said tube ends are included between the opposite ends of said flanges.

2. A muffler for silencing gases comprising a housing having an inlet and an outlet, means inside said housing

for conveying gases from the inlet to the outlet and silencing gases within the housing, said means including a straight tube having opposite end edges that lie in flat planes that are parallel to each other, a tube support member in said housing having an opening in a face thereof to receive an end of said tube and having an annular tube support surface adjacent to said opening so that one end of said annular surface defines said opening, said tube having an end extending into said opening and supported on said annular surface, said opening defining a flat plane that is non-parallel to the plane defined by the end of the tube extending through it so that the length of tube that is supported on said annular surface varies as measured along lines on the support surface which are perpendicular to the plane of the opening.
